Primary Examiner — Cynthia Ramirez*Assistant Examiner* — Gino Colan(74) *Attorney, Agent, or Firm* — Schwegman, Lundberg & Woessner, P.A.(57) **CLAIM**

The ornamental design for a reveal trim piece, as shown and described.

DESCRIPTION

FIG. 1 is a perspective view of a reveal trim piece, showing my new design;

FIG. 2 is a top plan view thereof;

FIG. 3 is a bottom plan view thereof;

FIG. 4 is a front elevational view thereof;

FIG. 5 is a back elevational view thereof;

FIG. 6 is a first side elevational view thereof; and,

FIG. 7 is a second side elevational view thereof.

The broken lines depict environmental subject matter only and form no part of the claimed design.

1 Claim, 4 Drawing Sheets(56)
